SPECTACLE CASE OR SIMILAR ARTICLE

Joseph A. Hueber and Edward K. Hueber, Penn Valley,
Pa., assignors to Kelly & Heuber, Inc., Philadelphia,
Pa., a corporation of Pennsylvania

Filed Oct. 21, 1965, Ser. No. 87,704

Term of patent 14 years

(Cl. D57—1)

FIG. 1.

FIG. 2.

FIG. 3.

FIG. 4.FIG. 5.FIG. 1 is a perspective view of a spectacle case or similar article shown in open position, embodying our new design;

FIG. 2 is an end elevational view thereof taken from the left of FIG. 1;

FIG. 3 is an end elevational view of the case in closed position;

FIG. 4 is a side elevational view thereof; and

FIG. 5 is a top plan view thereof.

The end not shown is a mirror image of the end shown. The side not shown has substantially the same appearance as the side shown.

We claim:

The ornamental design for a spectacle case or similar article, as shown and described.
